UNITED STATES PATENT OFFICE.

WILHELM SCHMIDT, OF WILHELMSHÖHE, NEAR CASSEL, GERMANY.

PISTON-VALVE FOR STEAM-ENGINES.

SPECIFICATION forming part of Letters Patent No. 750,400, dated January 26, 1904.

Application filed September 27, 1901. Serial No. 76,770. (No model.)

To all whom it may concern:

Be it known that I, WILHELM SCHMIDT, a subject of the King of Prussia, German Emperor, and a resident of Wilhelmshöhe, near 5 Cassel, in the Province of Hesse-Nassau, German Empire, have invented certain new and useful Improvements in Piston-Valves for Steam-Engines, of which the following is an exact specification.

10 My invention relates to improvements in piston-valves for steam-engines, and has especially for its purpose to provide a solid piston-valve without any piston-rings, in which piston-valve means are provided to avoid a wearing out of the valve-piston and of the valve-chest.

15 My invention is represented in the accompanying drawings, in which—

Figure 1 is a longitudinal section of the valve-chest provided with my new arrangement. Fig. 2 is a cross-section on line A B of Fig. 1. Fig. 3 is a longitudinal and a cross section of a modified construction of the valve-piston. Fig. 4 is a section on line C D of Fig. 1.

20 It is known that piston-valves with solid pistons without any piston-rings have the great advantage of a simple construction in which the wearing out of the valves is nearly perfectly avoided. Up to date it was not possible to use such solid valve-pistons for large engines, as in case the valve-pistons were fitted in tight enough to avoid great losses of steam a fraying and chocking of the pistons easily took place on account of differences in 25 the heating of the piston and the valve-chest and the different expansion hereby effected. In order to avoid this disadvantage, I provide means for equally heating the valve-piston and the valve-chest and herewith effecting always an equal expansion of these parts.

25 The piston-valves are constructed for double admission after the manner of the so-called "trick-valves." Contrary to the constructions known up to date the admission takes place from the middle of the valve-chests between the two valve-pistons. This arrangement has the advantage that in case of superheated steam being used the stuffing-boxes work only in the exhaust-steam, and only a very small 30 part of the valve-chest comes in contact with

the superheated steam. The valve-pistons *a* are situated in removable bushings *b*, in which an annular channel *b'* is provided. This channel *b'* can either be cast in, as shown on the right-hand side of Fig. 1, or a groove can be 55 turned in, which groove is closed by the valve-chest cover *c*, as shown on the left-hand side of Fig. 1. The annular channels *b'* are connected with the admission-room by means of channels *s*, situated on the outside of the bushings, so that in case the steam enters the valve-chest this steam immediately enters the channels *s* and the annular channels *b'*, hereby effecting an equal heating of the whole bushings *b*. 60

65 In order to attain a still better effect, the valve-pistons can be constructed so as to avoid too rapid a heating of the same. In order to attain this, an isolating-cover *d* may be provided at the inside of the valve-piston, leaving an annular channel *a'* between this cover and the piston proper, as shown on the right-hand side of Fig. 1.

70 In Fig. 3 another construction of the valve-piston *a* is shown. In this construction the 75 annular channel *a'*, situated at the side toward the entrance of the steam, is connected, by means of channels *t*, with the other side of the piston—that is to say, with the side at which the exhaust-steam leaves the valve-chest. It 80 is hereby attained that the exhaust-steam enters the channel *a'* through the channels *t* and herewith effects a cooling of the valve-piston.

85 In case of large valve-chests a still better and more equal heating of the bushings *b* can be attained by providing a second annular channel *b'* around these bushings.

90 In case of highly-superheated steam being used it will be advantageous to provide at the same time means for heating the bushings *b* and preventing too rapid a heating of the pistons *a* or effecting a cooling of the same.

Having thus fully described the nature of this invention, what I desire to secure by Letters Patent of the United States is— 95

1. In piston-valves for steam-engines, the combination with a valve-piston, of a removable bushing forming the valve-seat, annular channels provided in said bushing, and channels connecting said annular channels to the 100

admission-chamber, substantially as described and for the purpose set forth.

2. In piston-valves for steam-engines, the combination of the valve-piston, an annular channel provided in said piston, and channels connecting this annular channel with that side of the piston situated toward the exhaust-pipe, of a removable bushing forming the valve-seat, annular channels provided in said bushing, and channels connecting these annular channels to the admission-chamber, hereby

heating the bushings by the admission-steam and the piston by the exhaust-steam, substantially as described and for the purpose set forth.

In testimony whereof I have signed my name to this specification in the presence of two subscribing witnesses.

15 WILHELM SCHMIDT.
